ELECTRIC ALARM AND INDICATING DEVICE

John A. McLaren, Los Angeles, Calif.

Application October 6, 1945, Serial No. 620,800

3 Claims. (Cl. 177—325)

1

This invention relates generally to the art of signals and indicators, and more particularly to devices adapted to warn of a predetermined condition existing at a location remote from the device.

It is an object of this invention to provide a combined alarm and indicator particularly adapted, although not necessarily, for association with a refrigeration or an air conditioning system, to give an audible and visual signal at a convenient location such as the kitchen, should the correct operating temperature of the system fail to be maintained by a remotely located refrigeration or air conditioning unit, so that a sufficiently advance warning will be given to prevent loss or inconvenience should the unit not be functioning properly; should the current supply fail either temporarily, or by a burned out fuse, or by inadvertent or accidental removal of the electric plug from the source of current supply.

It is another object of this invention to provide an alarm and indicating system or device of the above described character which is composed of a simple, rugged and relatively inexpensive structure of neat and attractive appearance, whose parts positively co-act to give a dual warning in the event of improper functioning of the system which it is operatively connected with remotely, by sounding an alarm and rendering a visual indicator active for observation at any time, so that should the alarm be sounded when no one is in attendance, and ceases before anyone is in hearing distance, the visual indication will remain as a constant warning, all to the end of affording maximum protection to the owner against loss or inconvenience incident to failure of the refrigeration or air conditioning system to function properly.

With these and other objects in view, the invention resides in the combinations and arrangements of elements as set forth in the following specification and particularly pointed out in the appended claims.

In the accompanying drawing,

Figure 1 is a vertical longitudinal sectional view of one form of alarm and indicating device embodying this invention;

Figure 2 is a horizontal sectional view taken on the line 2—2 of Figure 1;

Figure 3 is a fragmentary view similar to Figure 1, and illustrating a second form of alarm and indicating device embodying this invention;

Figure 4 is a fragmentary view in front elevation of a third form of alarm and indicating device embodying this invention;

Figure 5 is a fragmentary view similar to Figure 1, and illustrating a fourth form of alarm and indicating device embodying this invention; and

Figure 6 is a view in front elevation partly

broken away, of the form of the invention shown in Figure 5.

Referring specifically to the drawing and particularly to Figures 1 and 2, this form of the invention is composed of a streamlined case C of sheet metal which includes a rectangular back or supporting plate 10 having top and bottom flanges 11 and 12, and a removable front cover 13 adapted to be secured to the back plate 10 by suitable lugs 14 on the plate receiving screws 15 on the cover.

Within the casing C is an alarm device A and an indicating element I operatively associated therewith. This alarm device may comprise a conventional form of electric bell or buzzer whose base 20 is secured to the plate 10 by bolts 21, and supports the usual stationary electromagnet 22, a vibrating armature 23 mounted on the base 20 by a spring 24 and having a clapper 25 disposed to strike the bell 26. Current for operating the bell may be supplied by a local battery of 6 volts provided by three series-connected dry cells 27 supported in a row on the bottom flange 12 of the case at one end of the latter, and confined against displacement by a partition 28. This bell circuit includes conductors 29 and 30 with which the cells 27 and the bell are in series, are connected to terminal sockets 31 and 32 mounted on the bottom flange 12. Jacks 33 and 34 are adapted to be plugged into these sockets and are carried by conductors 35 and 36 which lead to a remote location at which the refrigeration, air conditioning or other apparatus which incorrect operation is to be warned against.

The conductors 35 and 36 are connected to contacts 37 and 38 of a conventional thermostatic or pressure controlled switch S located at the unit so as to directly subject to variations in the temperature or pressure in the unit as the case may be. This switch includes a diaphragm 39 carrying a bridging contact 40 for the contacts 37 and 38, and is adapted to respond to a predetermined dangerous temperature rise in the cold chamber of a refrigerating unit, by expanding a gas in the thermostatic tube 41 of the switch S sufficiently for the contact 40 to close the normally open bell circuit so as to ring the bell 26 and thus sound an alarm to warn of the incorrect operation of the unit.

The indicating element I comprises a light-weight arm 50 having a suitable warning indicia such as the word "Danger" thereon, which arm is pivotally mounted about a fixed axis 51 on the plate 10 adjacent the alarm device A and in close proximity to the end of the case C. The case is provided with an opening in the form of a slot 52 disposed to freely pass the arm 50 during movement thereof from its non-signaling concealed position within the case as shown in full lines in Figure 1, to its signaling position wherein

it projects horizontally through the slot 52 as shown in broken lines in this figure.

Connected at 53 to the arm 50 adjacent its axis 51, is one end of a chain or cord 54 which constitutes an operative connection between the arm and a movable part of the bell, in the present instance the armature 23 to which the other end of the cord 54 is connected at 55. In its normal non-signaling position, the arm 50 is tilted slightly from the perpendicular in a direction to gravitate inwardly of the case, and is maintained in that position by the cord 54 which is pulled taut under this gravitating action of the arm, as shown in full lines in Figure 1.

However, upon closing of the bell circuit at the contacts 37 and 38, the initial attraction of the armature 23 by the electromagnet 22, jerks the cord with sufficient force to tilt the arm 50 in a direction outwardly of the case, so that the arm positively gravitates to its signaling position shown in broken lines in Figure 1. With the arm 50 in signaling position, the distance between the points of connection 53 and 55 of the cord 54 to the arm and armature, respectively, has been shortened sufficiently for the cord to be slack as shown in broken lines in this figure, and thus enable free and unrestricted ringing of the bell to be effected.

It will be clear that should there be no one in attendance at the device or in hearing distance of the bell during the period it is ringing until the battery cells become exhausted, the arm 50 will provide a constant and permanent indication for observation at any time later, thus providing further assurance that the warning given by the device will be noticed.

In the form of the device shown in Figure 3, there is substituted for the flexible connection 54 a lug 60 on the bell armature 23a which co-acts with a lug 61 on the indicating arm 50a to normally retain the latter in the slightly outwardly tilted non-signaling position shown in full lines, against the action of gravity tending to swing the arm downwardly and outwardly of the case C1 through the slot 52a to the signaling position shown in broken lines. Thus, completion of the bell circuit will disengage the lug 60 from the lug 61 upon initial attraction of the armature 23a by the electromagnet, to render the arm 50a free to gravitate to signaling position.

In the form of the invention shown in Figure 4, which may include either of the above described operating mechanisms for the signal arm, the case C2 is provided with a window 70 suitably located to expose the arm 50b to view within the case when the arm has moved to its signaling position, thus confining all moving parts in the case.

In the form of the invention shown in Figures 5 and 6, the warning indicia 80 such as the word "Danger" can be applied to a conveniently visible wall 81 of the case C3 and can be normally covered by a shield element 82 pivoted on the case at 83 and urged by a suitable hinge spring 84 to the lowered position shown in broken lines in Figure 5, to expose the warning indicia to view.

A spring-pressed latching pin 85 mounted in the case C3, normally co-acts with a keeper 86 on the element 82 to latch the latter up in the non-signaling position shown in full lines in Figure 5. A cord 87 or other flexible operative connection is trained over a pulley 88 in the case, and is connected to the latch pin 85 and to the bell armature 23b so as to release the latching pin from the keeper 86 in response to initial at-

traction of the armature by closing of the bell circuit, whereby the element 82 will be free to be moved by the spring 84 to its signaling position.

It will be manifest that in all forms of the invention, the activation of the audible signal will cause a visual indication to be given and maintained for observation at any time. It will be noted from Figure 1 that if it is desired, a push button switch 90 for testing the bell circuit can be mounted on the case C and connected across the conductors 29 and 30 so as to complete the bell circuit when the button is pushed.

I claim:

1. An alarm and indicating device comprising: an audible signal including an electromagnet and an armature vibrated thereby in response to the supply of current to the electromagnet; an indicating arm pivotally mounted about a fixed axis and normally gravitating in one direction to a non-signaling position; and a flexible connection between said arm and said armature, operable in response to initial attraction of the latter by the electromagnet when energized, to exert a pull upon said arm sufficient for the arm to gravitate in the other direction to a signaling position.
2. An alarm and indicating device comprising: an audible signal including an electromagnet and an armature vibrated thereby in response to the supplying of current to the electromagnet; an indicating arm pivotally mounted about a fixed axis and normally gravitating in one direction to a non-signaling position; and a flexible connection between said arm and said armature, operable in response to initial attraction of the latter by the electromagnet when energized, to exert a pull upon said arm sufficient for the arm to gravitate in the other direction to a signaling position; said flexible connection being drawn taut by said arm when gravitating to non-signaling position, so as to act in determining such position of the arm; said flexible connection being slack when said arm occupies signaling position so as to render said armature free to continue vibrating.
3. An alarm and indicating device comprising: a case having a vertical slot in an exterior wall thereof; an alarm device in the case including an electromagnet and an armature vibrated thereby when current is supplied to the electromagnet; an indicating arm pivoted about a horizontal axis adjacent said slot to mount the arm for movement from a non-signaling position in the case to a signaling position wherein the arm projects from the case through said slot; and a flexible member connected to said arm and to said armature to normally be pulled taut by the arm in tending to gravitate to non-signaling position; said member being responsive to movement of the armature by the electromagnet when energized, to jerk the arm sufficiently for the latter to reversely gravitate to signaling position, with said member being slack following such operation thereof, so as to render the armature free for vibration as aforeslated.
